GEORGE E. STEVENS, OF LACONIA, NEW HAMPSHIRE, ASSIGNOR OF ONE-HALF TO
FRED S. ROBERTS, OF LACONIA, NEW HAMPSHIRE.

PIPE CLEANER.

1,402,107.

Specification of Letters Patent. Patented Jan. 3, 1922.

Application filed May 1, 1920. Serial No. 378,117.

To all whom it may concern:

Be it known that I, GEORGE E. STEVENS, a citizen of the United States, residing at Laconia, county of Belknap, State of New Hampshire, have invented an Improvement 5 in Pipe Cleaners, of which the following description, in connection with the accompanying drawing, is a specification, like characters on the drawing representing like parts.

This invention relates to pipe cleaners and has for its principal object to provide a pipe cleaner having a novel holder which operates not only to receive and hold the 5 cleaner when it is not in use, but also which operates as a hand-hold by which the pipe cleaner may be manipulated while it is being used to clean a pipe.

In order to give an understanding of my 0 invention, I have illustrated in the drawings a selected embodiment thereof which will now be described, after which the novel 5 features will be pointed out in the appended claim.

5 In the drawings, Fig. 1 is a perspective view showing the manner in which my pipe cleaner is used for cleaning a pipe;

Fig. 2 is a perspective view showing the 0 pipe cleaner coiled up and confined within the holder or casing;

Fig. 3 is a sectional view through the holder or casing with the pipe cleaner therein.

My improved pipe cleaner which is indicated generally at 1 is preferably formed 5 from a length of wire which is wound into a small coil having the turns in contact with each other. A pipe cleaner of this nature is flexible and can be readily inserted into 0 the bore of the pipe stem and the surface thereof is sufficiently rough so that it will effectively clean the pipe stem. Moreover, it is flexible enough so that when the end thereof is forced completely through the 5 pipe stem into the bowl of the pipe 5, the end will bend or flex as it strikes the wall of the bowl.

To be effective a pipe cleaner of this type must have a length somewhat longer than 0 the length of the pipe stem. It is also desirable to have a pipe cleaner of this sort so constructed that it can be readily folded or rolled into a sufficiently compact space to permit it to be carried in the pocket. 5 Further, in using a pipe cleaner of this sort

it is an advantage to have at one end thereof a finger-piece or hand-hold of sufficient size so that a person can readily grasp it because the diameter of the pipe cleaner itself is quite small and it is not easy to hold it. 60

I have, therefore, by my invention provided a combined casing and hand-hold for the pipe cleaner which operates as a closure or casing into which the pipe cleaner can be rolled up when it is to be carried in the 65 pocket and which also constitutes a finger-piece or hand-hold by which the pipe cleaner may be manipulated while it is used for cleaning the pipe. This combined holder or casing and hand-hold is in the form of 70 a box 2 which is provided with a cover 3. The box 2 is preferably cylindrical in shape and one end of the pipe cleaner is rigidly secured to the bottom of the box 2, as shown at 4. I will preferably secure the end of 75 the pipe cleaner to the box at the corner of the bottom but the particular location in the box where it is secured is not essential. The pipe cleaner may be fastened to the box in any suitable way without departing from the invention. One way would be to solder or sweat the end of the pipe cleaner thereto, or it might be fastened thereto by rivets or in any other suitable way. It will, however, preferably be so 80 secured to the box that when it is released from the box it will extend therefrom at about the angle shown in Fig. 1 which is approximately 45°. When the pipe cleaner is not in use it can be coiled up and laid 85 within the box, as shown in Figs. 2 and 3, and when the cover 3 is applied the pipe cleaner will be entirely enclosed within its casing and may be carried in the pocket without danger of its soiling any article 90 with which it comes in contact.

The box 2 may be made small enough so that it can be readily carried in the vest pocket or any other small pocket without 95 inconvenience.

When the pipe cleaner is to be used the cover 3 is removed from the box and the pipe cleaner is then withdrawn from the box, and it will then extend outwardly from the box, as shown in Fig. 1. The box 2 105 may then be used as a thumb-piece or hand-hold for holding the pipe cleaner while it is used for cleaning the pipe. The box makes a very convenient hand-hold for this purpose because it is large enough so that 110

it can be readily grasped between the thumb and finger of the hand, and by means of it the pipe cleaner can be manipulated much more easily than if it was necessary to grasp the relatively small pipe cleaner.

Fig. 1 shows how the device is ordinarily used, the pipe 5 being held in one hand and the combined holder and case 2 of the pipe cleaner being held in the other hand.

10 It will be seen that with my invention the casing 2 not only operates as an envelope or casing to receive the pipe-cleaning element when it is not in use, but it also constitutes a convenient hand-hold by which 15 said element can be manipulated.

I claim:

The combination with a casing comprising a cylindrical body having a closed bottom

and an open top and a cover separable from the body and detachably applied thereto, 20 of a flexible pipe-cleaning element having one end rigidly secured to the interior of said body at the corner between the bottom and side wall in such fashion that said element normally extends from the body at an 25 angle of approximately 45 degrees to the bottom thereof, but can be coiled up within the body, whereby when the pipe-cleaning element is extended from the body, said elements can be manipulated for cleaning a 30 pipe by grasping the circular sides of the body between the thumb and finger.

In testimony whereof, I have signed my name to this specification.

GEORGE E. STEVENS.
